UNITED STATES PATENT OFFICE

GEORGES SICK, OF LAUSANNE, SWITZERLAND

HEATED MASSAGE DEVICE

Application filed October 19, 1928, Serial No. 313,575, and in Switzerland October 24, 1927.

The present invention relates to heated massaging devices and, more especially, to those of the type which are electrically heated.

5 One of the objects of the invention is to provide a massaging device which may be slowly heated to the temperature desired and maintained there at during a comparatively long period of time without danger of scorching the skin to which it is applied.

10 Other objects will appear in the course of the detailed description now to be given with reference to the accompanying drawings in which:

15 Fig. 1 is a section through one constructive embodiment of the invention;

• Fig. 2 shows, in section, a slightly modified form of the device represented in Fig. 1;

20 Fig. 3 is an elevation of a second possible form of the invention.

Referring to Figs. 1 and 2 of the drawings, there is shown a massaging assembly consisting of a hollow shaft *a* carrying a pair of handles *b*,—a helicoidal resistance *c* spirally wound on shaft *a*,—a two-wire cable *c*¹ for supplying current to resistance *c*,—an external massaging shell *e* having indentations, corrugations or the like formed thereon and freely rotatable on shaft *a*,—a layer of heat insulating material *f* interposed between elements *c* and *e*, and formed of superposed layers of asbestos held together by a binder, or of porcelain, plaster, brick or any other substance capable of storing the heat given

25 off by resistance *c* and slowly transmitting the heat so accumulated to shell *e*,—an insulating supporting shell *j* for resistance *c* (ebonite, porcelain or metal covered with insulating material),—and asbestos rings *k* 30 adapted to heat insulate shell *j* from shaft *a*.

The essential novelty in the present invention lies in the structure of the combined wall *e*, *f*. In the prior art devices, the latter has been formed of a relatively thin sheet of 35 metal corresponding to element *e* which conducts the heat so rapidly from resistance *c* that either the subject being massaged is exposed to the danger of being scorched or else the operator is subjected to the annoyance of 40 having to repeatedly pull cable *c*¹ from its

socket during the massaging operation. By interposing a layer of heat-storing material between *c* and *e*, the temperature of *e* gradually rises during the course of massaging and the subject being massaged is able to better 45 support relatively high temperatures. Moreover the device may be used continuously without having to pull cable *c*¹ from its socket.

It is to be understood, of course, that, while elements *e* and *f* have been shown separately—this being a preferred form of the invention—they may be replaced by a single relatively thick wall of metallic or other appropriate material having a large heat capacity. It will be noted, however, that by 50 providing a thin external wall of metal (*e*) and an internal layer of heat insulating material (*f*), a structure combining high heat capacity and very light weight is obtained.

The structure shown in Fig. 2 differs from 55 the one represented in Fig. 1 only in providing means for changing external wall *e* so as to vary the shape of the protuberances formed thereon. Here elements *e* and *f* are separated by a layer of wire-gauze or perforated metal *h* adapted to maintain substance *f* in position when wall *e* is removed. Wall *e* is supported between a removable end-element *f*¹ and a non-removable element *f*². By unscrewing threaded ring *f*³, and sliding 60 end-element *f*¹ off of shaft *a*, wall *e* may be removed and replaced by a similar element of desired shape. Obviously element *f*¹ may be made non-removable and *f*² removable.

The structure represented in Fig. 3 is a 65 single-ended heated massaging device intended to be used on special parts of the body. The massage roll *d* is here provided with hemispherical extremities and is supported on a rigid curved arm *q* carrying cable *c*¹ 70 and covered by a heat insulating material *q*¹ such as varnish or shellac for preventing accidental scorching of the skin when arm *q* contacts therewith. To further heat insulate arm *q*, a heat insulating segment *q*² 75 formed of porcelain, mica, asbestos or the like may be interposed between the massage roll and arm *q*.

What I claim is:—

A massage instrument comprising a hol- 100

low shank, a sleeve of insulating material carried by said shank in fixed relation thereto, an electrical heating coil mounted on said sleeve, and a rotatable massage roll rotatably carried by said shank completely enclosing said heating coil but spaced therefrom, said massage roll having an external composite wall composed of an exterior applicator shell and an inner layer of solid refractory heat storing material lining said shell, said lining being exposed directly to the heat radiations of the coil and means passing through said shank for conducting current to said coil.

10 In testimony whereof I have signed this
15 specification.

GEORGES SICK.
